United States Patent Office

Des. 194,635

Patented Feb. 19, 1963

194,635

BOTTLE

Richard L. Platte, Ann Arbor, Mich., assignor to Hoover Ball and Bearing Company

Filed July 23, 1962, Ser. No. 71,007

Term of patent 14 years

(Cl. D58—8)

The side and end not shown are substantially the same as the side and end shown.

I claim:

The ornamental design for a bottle, as shown and described.
